John H. Knight & Joseph P. Connell of Detroit, Mich.

Letters Patent No. 2477, dated Oct. 2, 1866.

Design for a Cigar & Tobacco Safe.

The Schedule referred to in these Letters Patent and making part of the same.

To all whom it may concern,

Be it known that we, John H. Knight of the United States Army, and Joseph P. Connell of the City of Detroit in the County of Wayne and State of Michigan, have originated and produced a new and ornamental Design for a Cigar and Tobacco safe, of which the following is a full, clear and exact description, reference being had to the accompanying drawings making part of this Specification.

Our invention consists of a Cigar and Tobacco safe, so made with cigar cupboards and holder, lightholder, tobacco drawer, match cups, and friction surface, for lighting matches, as to form, at the same time, a compact, and convenient receptacle for cigars and tobacco, and a highly ornamental piece of furniture for a room, to the wall of which the safe is intended to be attached.

In the accompanying drawing A, B, represents a shield-shaped dish, which may be made of any desired size, but we consider a size of two feet from A, to B, and twenty-one inches in its widest part, the most desirable size for the dish, and the dimensions hereinafter given are to be understood as appropriate for a dish of that size.

Across the face of the dish A, B, and sufficiently low to bring its ends flush with the edges of the dish is fastened a cross shelf a, b, which for the size of dish above given should be fifteen and one half inches long, and five and one half inches wide.

Upon the shelf a, b, and attached to the face of the dish A, B, are two cupboards C, C, for cigars, each divided by a horizontal shelf into two equal compartments. These cupboards are closed by hinged doors opening outwardly.

The appropriate dimensions for the cupboards are as follows: Seven and one half inches high, four and one fourth inches wide, and five and one eighth inches deep. Upon the top of the cupboards C, C, are placed two goblet shaped vases for cigars marked D, D, in the drawings.

The appropriate dimensions for the cigar cases are as follows: Height six inches, circumference nine inches, inside depth, three inches inside diameter two, and three fourths inches.

The space between the cupboards C, C, is divided midway by a horizontal shelf, beneath which is a drawer E, for smoking tobacco, the appropriate dimensions of this drawer, on a dish of the size mentioned are, Depth five and one eighth inches. Width, four and one half inches and height three and one half inches.

Upon the face of the dish A, B, and immediately beneath the upper middle point A, is attached a holder F, for lighters. Appropriate dimensions length, five inches, Depth inside three and one fourth inches and Width two and five eighths inches.

Des 2477

26

Also upon the face of the dish and between the cross shelf a, b, and lower point B, of the dish are attached two match cups c, c, of which the following are appropriate dimensions.—Length three inches.—Depth inside two inches, and width one and seven eighths inches.

Directly above the match cups c, c, and attached to the under side of the cross shelf a, b, is a piece of sand paper or other friction surface for igniting matches, this is not shown in the drawings.

The material of which the cigar and tobacco safe is intended to be made is wood of any desirable kind.

The dish A, B, cross shelf a, b, cupboards D, C, and tobacco drawer E, may be made three eighths of an inch in thickness, and the holders or pads D, D, the light holder F, and match cups c, c, are turned from the same kind of wood of the dimensions given above. What we claim as our invention and desire to secure by Letters Patent is, The Design or Pattern of a cigar and tobacco safe as herein described and shown.
